UNITED STATES PATENT OFFICE.

JOSEPH E. HAGEL, OF ZABRISKIE, CALIFORNIA.

CALENDAR-WATCH.

1,190,155.

Specification of Letters Patent.

Patented July 4, 1916.

Application filed September 3, 1915. Serial No. 48,809.

To all whom it may concern:

Be it known that I, JOSEPH E. HAGEL, a citizen of the United States, and a resident of Zabriskie, in the county of Inyo and State 5 of California, have invented a new and useful Improvement in Calendar-Watches, of which the following is a specification.

My invention is an improvement in calendar watches, and the invention has for its 10 object to provide a ring capable of attachment to the ordinary dollar watch in such position that it will encircle the dial and will be rotatable on the watch case, the ring bearing on its outer face the days of the 15 months in sequence to permit any predetermined day to be brought into register with one of the numbers of the dial, as for instance, 12 to indicate the day of the month.

In the drawings: Figure 1 is a front view 20 of a watch provided with the improved calendar, and Fig. 2 is an edge view of the watch with the ring in section.

The present embodiment of the invention is shown in connection with the case 1 of 25 a watch of usual construction having the ring 2 and the stem set 3. The crystal 4 of the watch is held in the usual ring 5, which is connected with the body of the case in the usual manner, and the ring permits the 30 dial 6 to be seen.

The improvement comprises a ring 7 of 35 suitable material, as for instance, metal, celluloid, or the like, the said ring being curved or arched transversely as shown and being approximately the frustum of a cone. At the large end the ring is provided with a laterally extending flange 8^a, which is adapted to engage over the ring 5, as shown, to hold the ring 7 in place. The diameter of 40 the small end of the ring is approximately that of the dial, so that the numbers 8 of the dial and the graduations 9 will not be hidden by the ring. The outer surface of the ring is divided into equal spaces by transverse lines 10, which are formed in any suitable or desired manner, and a series 11 of numerals is arranged in the spaces. These

numerals indicate the days of the months from one to thirty-one, and they are arranged consecutively, the designation of one 50 day of each month being in one of the spaces. The ring 7 is arranged to rotate on the watch to permit any numeral or group of numerals to be brought into register with the indication 12 on the dial, and 55 this indication is taken, as a rule, as an indicator for coöperating with the ring.

Since the greater portion of watch owners wind the watch once a day, it will be easy to remember to move the ring whenever the 60 watch is wound and the owner thus has a record of the day of the month, which, if he is careful to move the ring whenever he winds the watch, will be absolutely correct. In those months having thirty days or 65 twenty-nine days, the ring will be moved from thirty to one, or from twenty-nine to one on the last day of the month.

The improved watch is especially suitable 70 for prospectors, miners and other travelers to whom the ordinary calendar is not accessible. The ring is arranged to snap over the crystal ring 5 tightly enough, so that it will hold, and may yet be turned.

I claim:—

In combination, a watch provided with a bezel and having an annular bead, and a calendar attachment, the same consisting of a ring to overlie and fit close against the bezel and provided at its outer edge with a 80 flange to engage the bead and retain the attachment in place, said ring being arched and provided on its face with radial lines forming thirty-one regular spaces which receive numbers in successive order from one 85 to thirty-one inclusive corresponding to the days of the month, said ring being rotatable to bring the numbers in position opposite a given fixed point of the watch.

JOSEPH E. HAGEL.
